PROTECTED SWITCH OPERATING SYSTEM

Harry E. Brashares, St. Paul, Minn., assignor, by
mesne assignments, to Union Switch & Signal
Company, Swissvale, Pa., a corporation of
Pennsylvania

Application March 3, 1924, Serial No. 696,436

17 Claims. (Cl. 246—240)

The present invention relates to train control, and more particularly to an improved means for actuating a track switch from a moving train.

An enormous amount of energy is required to stop and start a train, and, where long freight trains are pulled by powerful locomotives such as those of the Mallet type, damage to drawbars and other car paraphernalia caused by the strains of starting and stopping is of common occurrence. It is desirable, therefore, to cut down the number of startings and stoppings required to a minimum, while maintaining a positive safety factor in the manipulation of trains.

To this end the present invention is designed. An object of the present invention is to improve and simplify a protected switch mechanism operable from a moving train.

Another object is to operate a switch from a moving train and after such operation to stop the train if it is not safe for the train to enter the switch.

A further object is to operate a switch from a moving train and to indicate to the attendants thereof the condition of traffic on tracks associated with the switch.

In order to attain these objects I employ, in accordance with one form of my invention, an electro-magnet of a well-known type adjacent the path of an oncoming train, as, for instance, in a box imbedded between the rails. This electro-magnet may be intercepted by an electromagnetic field generated by some means carried by the oncoming train, as, for instance, by a permanent magnet, to induce a current into the coils of the electro-magnet, to actuate switch operating, signaling, and protective devices to be more fully described hereinafter.

The accompanying drawing shows the apparatus and method of operation of one embodiment of my invention.

Referring to the drawing in detail:

A, B, C, and D represent track circuits on a main line track, while E and F represent track circuits on a side track. The ends of adjacent track circuits being separated indicate insulated joints at these points. Batteries 1, 2, and 3 are connected across the rails of track sections B, C, and D, respectively, of main line track, to establish a permanent difference of potential between the rails of each of these track circuits.

The apparatus as here illustrated is arranged to permit a train, coming from the right over main line track A, B, C to enter the switch 4 and thence the side track E, F without stopping.

An electro-magnet 5 is here shown positioned

intermediate the rails of track section A, and the terminals of the winding of this electro-magnet are connected to the field of a relay 6. A magnetic-field generating device 7 is carried by the oncoming train, and may be a permanent magnet 5 so as to induce a current therein in passing, or not, as desired.

A relay 8 is connected across track circuit B and is held closed by track battery 1, except when a train is passing over B track. Such a passage short-circuits battery 1 and permits relay 8 to open. Relays 9 and 10 are similarly connected across track circuits C and D.

Track circuit A may be considered as about 15 half a mile in length, and track circuit B as about three thousand feet, or, in other words, sufficiently long to allow for effective braking, if necessary.

Signals are indicated by the conventions 11, 12, 13, and 14, and are electrically connected to the system as shown for a purpose to be fully explained hereinafter. The signals are here shown as of the semaphore type, but it is to be understood that any form of signal may be employed. Contacts 15, 16, 17, and 18 are positioned adjacent semaphore arms 11, 12, 13, and 14, respectively, and are operated by a movement of said arms in a manner to close an electrical connection across any of these contacts when the associated semaphore arm thereof is in a "stop" position.

A brake actuating mechanism 19 is provided to cause the brakes to be applied to an oncoming train, should any of the apparatus herein described, register conditions which would make it unsafe for the train to proceed. This brake actuating mechanism is actuated by the opening of a relay 37 connected as illustrated.

A switch operating motor 21 moves the switch 4 to side track position on being rotated in one direction, and to main line position when rotated in the other direction. Four pairs of contacts 22 are illustrated, and a pair of movable cross connections therefor are operated by the switch operating motor 21 and its associated mechanism, to close the upper and third pairs of contacts 22 when the track switch 4 is in side track position, and to close the second and the lower pairs of contacts 22 when the track switch 4 is in main line position. These pairs of contacts 22, as well as all relay contacts in this specification, will be designated by numbers reading from the top down, the upper or "make" contact of the relays being designated as "front" 55

and the lower or "break" contact being designated as the "back" contact.

All of the relays illustrated are standard, immediate action, gravity drop relays, except relay 5 23, which is designed to be delayed in closing a predetermined interval after energization of the field thereof.

Batteries 24, 25, 26, 27, and 28 are indicated by the standard convention therefor.

10 Manually operated keys 29 and 30 are of the "make" and "break" type, respectively.

The two leads at the left of the drawing marked X and the lead from the upper front contact of relay 8, also designated by X, all lead to other 15 automatic control circuits, but for the purpose of this specification may be considered as having a positive potential.

Circuits

20 The circuits involved in the present system are traced in detail in the following paragraphs.

The circuit for relay 6 is from the inductively energized member 5, through conductor 140, the coil of relay 6, and conductor 141 back to member 5.

25 Closure of relay 6 completes a circuit from the positive terminal of battery 28, through conductor 39, the front contact of relay 6, conductor 41, the second front contact of normally closed relay 30, conductor 42, the coil of relay 31, conductor 43, normally closed key 30, conductor 142, and conductor 44 to common negative 40.

30 The closure of relay 31 closes a locking circuit for relay 31 through the coil of relay 31, conductor 43, key 30, and conductor 44 to negative side of battery 26, and from the coil of relay 31, through conductor 45, the upper front contact of relay 31, conductor 46, the upper front contact of relay 9a, which is operated in conjunction with relay 9 (as 40 will be brought out later in the specification), conductor 47, battery 26, and conductor 48 to common negative 40.

35 This locking circuit is broken only by the opening of relay 9a in a manner which will be apparent after a study of the specification, or by 45 opening key 30 which may be placed at any point along the right of way as desired.

The circuit for the brake actuating mechanism 19 is from mechanism 19, through conductor 49, 40 front contact of relay 31, conductor 50, battery 27, 45 and conductor 51, back to mechanism 19. The normal condition of the brake operating mechanism is with the circuit closed, a release of the circuit through the opening of relay 31 moving the mechanism to an operative condition to set the brakes on a train passing over said mechanism. The relay 31 is designed to be held closed when either relay 34 or relay 36, or both, are operated, the alternate circuits of relay 31 being as follows: First,—With relay 36 closed and relay 34 open: 50 from common negative 40, through conductor 52, coil of relay 37, conductor 53, lower front contact of relay 36, conductors 54, 55, 56, 47, battery 26, and conductor 48 to common negative 40; Second,—With relay 36 open and relay 34 closed: 55 from common negative 40, through conductor 52, coil of relay 37, conductors 53, 57, lower front contact of relay 34, conductors 55, 56, 47, battery 26, and conductor 48 to common negative 40. With 60 both relays 34 and 36 closed both the above circuits would act to hold relay 37 operated.

65 As the train enters track section B it short-circuits the circuit of relay 8 by the wheels and axles of the cars. The circuit of relay 8 is from track battery 1, through rail 59, conductor 60,

the coil of relay 8, conductor 61, and rail 62 back to battery 1.

The circuit for relay 36 is from common negative 40, through conductors 44, 63, 64, the coil of relay 36, conductor 65, across the first pair of contacts of switch 22 when the track switch 4 is in sidetrack position, conductor 66 across the second front contact of relay 33, conductor 67, the third front contact of relay 9, and through conductor 68 to positive battery at X. The circuit for relay 34 is from common negative 40, through conductors 44, 63, 69, 70, the coil of relay 34, conductor 71, the second pair of contacts on switch 22, when the track switch 4 is in mainline position, conductor 72, the second front contact of relay 32, conductor 73, the second front contact of relay 9, conductor 74, the front contact of relay 10, and conductor 75 to positive battery X.

The circuit for signal 11 is through relay 36, and for signal 12 through relay 34, the circuits for said signals being as follows: Signal 11: from common negative 40, through conductors 44, 63, 69, 76, 77, signal 11, conductor 78, first front contact of relay 36, conductors 79, 54, 55, 56, and 47 to the positive pole of battery 26. Signal 12: from common negative 40 through conductors 44, 63, 69, 76, 80, signal 12, conductor 81, the first front contact of relay 34, conductors 82, 55, 56, and 47 to the positive terminal of battery 26.

It will be noted that the circuit for relay 34 as previously described which relay controls signal 12, passes through switch 22 when said switch is in mainline position, the second front contact of relay 32, the second front contact of relay 9, and the front contact of relay 10. Relay 10 is the track relay for track section D, the circuit therefor being from track battery 3, through rail 86, conductor 84, the coil of relay 10, conductor 85, and rail 83, back to battery 3. Relay 10 is closed except when a train occupies track section D, which shorts out relay 10 and opens the circuit for signal 12, moving it to a biased or "stop" position. Relay 9 is the track relay for track section C, and the circuit therefor is from track battery 2, through rail 90, conductor 88, the coil of relay 9, conductor 89, and rail 87, back to battery 2. This relay is also normally closed and is opened by the presence of a train on track section C in the same manner as relay 10. The relay 9a is controlled by a front contact of relay 9, the circuit for relay 9a passing from battery 24, through conductors 110, 109 and 108, first front contact of relay 9, winding of relay 9a, and conductors 48 and 40 back to battery 24. The switch 4 is actuated by motor 21, which motor is controlled by the following circuits, which circuits may be termed "normal" and "reverse", respectively. The "normal" circuit, which, when completed, moves track switch 4 and switch 22 to main line position is from common negative 40 through conductor 91, the field 92 of the motor, conductor 93, the fourth front contact of relay 32, conductor 94, the commutator 95 of the motor, conductor 96, the fourth back contact of relay 33, conductors 97, 98, the front contact of relay 23, and conductor 99, to the positive terminal of battery 25. This "normal" circuit, it will be noted, requires that relays 23 and 32 be closed and relay 33 open. The "reverse" circuit is as follows—from common negative 40 through conductor 91, the field 92, conductor 100, the fourth front contact of relay 33, conductor 96, armature 95, conductor 94, the fourth back contact of relay 32, conductor 101, conductor 98, the front contact of relay 23, and conductor 99 to the positive terminal of battery 25. The comple-

tion of the reverse circuit moves track switch 4 and switch 22 to sidetrack position. Relay 23 must be closed before either the "normal" or "reverse" circuits can be closed. Relay 23 is of the 5 delayed closing type, wherein there is a time interval between the energizing of the relay and the actual actuation thereof. The circuit for relay 23 is from common negative 40, through conductor 102, the coil of relay 23, conductor 103, the switch 10 15, which operates in conjunction with signal 11, conductor 104, switch 16, which operates in conjunction with signal 12, conductor 105, switch 18, which operates in conjunction with signal 14, conductor 106, switch 17 which operates in conjunction with signal 13, conductors 107, 108, 109, and 110 to the positive terminal of battery 24.

The circuit for relay 32 is, from common negative 40, through conductor 111, the second back contact of relay 31, conductor 112, the coil of relay 32, conductor 113, the first back contact of relay 33, conductors 114, 115, the second front contact of relay 9a, conductors 116, 56, and 47 to the positive terminal of battery 26. The circuit for relay 33 is from common negative 40, through 25 conductor 111, second front contact of relay 31, conductor 117, coil of relay 33, conductor 118, first back contact of relay 32, conductors 119, 115, the second front contact of relay 9a, conductors 116, 56, and 47 to the positive terminal of 30 battery 26.

The circuit for signal 14 is from common negative 40, through conductors 120, 121, 122, signal 14, conductor 123, the front contact of relay 35, conductor 124, and conductor 110, to the positive 35 terminal of battery 24. The circuit for signal 13 is from common negative 40, through conductors 120, 121, 125, signal 13, conductor 126, the front contact of relay 38, conductors 127, 109, and 110 to the positive terminal of battery 24.

40 The circuit for relay 35, which controls the operation of signal 14, is from positive terminal X, through conductor 128, the first front contact of relay 8, conductor 129, the third front contact of relay 9a, conductor 130, the fourth pair of 45 contacts of switch 22 when the switch is in the main line position, conductor 131, the third front contact of relay 32, conductor 132, the coil of relay 35, conductor 133, the fourth front contact of relay 9, conductor 134, and 120 to common negative 50 40.

The circuit for relay 38, which controls the operation of signal 13, is from the positive terminal X, through conductor 128, the first front contact of relay 8, conductor 129, the third front contact 55 of relay 9a, conductor 130, conductor 136, across the third pair of contacts of switch 22 when the switch is in a sidetrack position, conductor 137, the third front contact of relay 33, conductor 138, the coil of relay 38, conductor 139, the fourth 60 front contact of relay 9, conductor 134, and conductor 120 to common negative 40.

Operation

Consider that a train is approaching from the 65 right over main line track A, B, C and that the engineer desires to enter the side track E, F by means of switch 4. The device 1 carried by the locomotive is positioned so that a magnetic field generated thereby shall pass in proximity 70 to the electro-magnet 5. As this field passes the electro-magnet 5, the lines of force of the magnetic field induce a current into the coils of electro-magnet 5 to operate the relay 6. Closure of the contact of relay 6 completes the pick-up circuit 75 previously traced for relay 31. The closure

of relay 31 then completes the locking or stick circuit previously traced for this relay.

This locking circuit is broken only by the opening of relay 9a, or manually by means of key 30 placed along the right of way as desired.

Should a relay 34 governing the movement of signal 12 and a relay 36 governing the movement of signal 11, both be de-energized when the on-coming train is still on track A, thus moving signals 11 and 12 both to the "stop" position, a relay 10 37, normally energized, would be opened and cause the brakes to be applied and the train to be stopped by cooperation with associated apparatus carried by the train. The relays 34 and 36 would both be open under either of two conditions: first with the track switch 4 in side track position, thereby opening the circuit of relay 34 through the second pair of contacts 22, and at the same time with relay 9 open thereby opening the circuit of relay 36 through its third front contact; and second the switch 4 being in main line position thus opening the circuit of relay 36 through the first pair of contacts 22 and at the same time either relay 9 or relay 10 open thereby opening the circuit of relay 34.

A relay 32, which may be termed the "normal" relay, was held energized through the lower back contact of relay 31 before relay 31 was energized, and through the upper back contact of a relay 33, which may be termed the "reverse" relay. When 30 relay 31 was energized as previously explained, normal relay 32 was released, opening its front contacts and closing its back contacts. This opened the circuit controlling the forward movement of switch operating motor 21, at the same 35 time, the reverse motor control circuit, through relay 33, was placed in condition to be closed through the upper back contact of relay 32 and lower front contact of relay 31, as soon as time relay 23 is energized in a manner to be described 40 in the following paragraph. When time relay 23 is energized, it completes the circuit through the motor 21 in a manner to reverse it, thereby causing switch 4 to be moved to the side track position and, upon the completion of the switch 45 throwing operation, the closure of the upper and the third pairs of motor operated contacts 22.

Opening of the second and third front contacts of normal relay 32 causes the release of relays 34 and 35, respectively. The opening of relay 34 50 causes signal 12 to move to the "stop" position, and the opening of relay 35 causes signal 14 to move to the "stop" position. The moving of these signals to the "stop" position closes the contacts 16 and 18, respectively. Signal 11 is held in "stop" 55 position when motor contacts 22 are in main line position, the upper pair of contacts 22 being open, since this opens the circuit for relay 36. Signal 13 is also held in "stop" position when track switch 4 is in main line position, since the third pair of 60 contacts 22 are then open, thus opening the circuit through relay 38 governing signal 13.

The opening of relay 32, therefore, brings all the signals, 11, 12, 13, and 14, to the "stop" position, closing their associated contacts 15, 16, 17, 65 and 18 and energizing relay 23 which, after a predetermined time interval, closes and completes the reverse circuit through motor 21 to throw switch 4 to side track position. If the switch throwing operation is completed and the upper 70 and the third pairs of contacts 22 are thereby closed, the circuit for relay 38 which controls signal 13 is completed through the third front contact of relay 33 and the third pair of contacts 22, moving signal 13 to the "proceed" position. At 75

- the same time, the circuit for relay 36 which controls signal 11 is completed through the upper pair of contacts 22, the second front contact of relay 33, and the third front contact of relay 9. 5 The moving of signal 11 to "proceed" position opens contact 15 and returns time relay 23 to normal.

When the train passes signal 11 onto track circuit C, track relay 9 opens, which opens the circuit of relay 9a also. 10 This opens relay 36 returning signal 11 to "stop" position, and also opens the locking circuit for relay 31, by opening the upper front contact of relay 9a, thereby opening the reverse relay 33.

- 15 The opening of the lower front contact of relay 31 also opens the circuit of reverse relay 33 at another point, and the closing of the lower back contact of relay 31 places normal relay 32 in condition to be energized as soon as the train passes 20 track circuit C to cause relays 9 and 9a to close again.

The opening of relay 33 opened the circuit of relay 36 at another point. Signal 13 was moved to the "stop" position upon the opening of relay 8 25 when the train entered B track circuit, and is held open through relay 9a when the train enters C track circuit. All of signals 11, 12, 13, 14, are in the "stop" position at this time and the circuit of relay 23 is complete through contacts 15, 16, 17, 30 and 18.

As soon as the train clears track circuit C relays 9 and 9a close, thereby completing the circuit of normal relay 32 to cause it to operate. The operation of relay 32 closes the normal motor 35 circuit from positive battery through the contact of time relay 23, the lower back contact of reverse relay 33, the motor armature, lower front contact of relay 32, the motor field, and thence to negative battery. This moves the track switch 4 to 40 main line position, closing the circuit for relay 35 through the lower pair of contacts 22, which moves signal 14 to "proceed" position and also closes the second pair of contacts 22 in the circuit for relay 34, permitting this relay to become 45 energized when the front contact of relay 10 has been closed and when other traffic conditions by which relay 34 is controlled are suitable.

To move out of the side track an electro-magnet similar to 5 energized by an induced current 50 may be used to re-operate the system, or a manually operated key 29 may be placed adjacent the right of way as desired and closed to operate the system. The pick-up circuit for relay 31 controlled by key 29 passes from battery 26, through 55 wire 41, upper front contact of relay 9a, wire 46, key 29, winding of relay 31, wire 43, key 30, and wires 142, 40 and 48 back to battery 26.

If, after energizing relay 6 and starting the system to operate, it should be desired to proceed on 60 the main line, opening of key 30 will return the system to normal, bringing track switch 4 back to main line position.

It will be seen, from the preceding, that the system covered by the invention provides a safe 65 and positive means for operating a switch from a moving train, and one which may be used in co-operation with existing apparatus used in manipulating trains. An important feature lies in the fact that the system may be installed without the 70 necessity of providing cumbersome, extraneous apparatus carried by the locomotive or train.

What I claim is:

1. A railroad switch operating system comprising a switch, a signal governing traffic over the same, means on the train co-operating induc-

tively with means on the roadside to operate said switch and effective only when said signal indicates "stop".

2. A railroad switch operating system, comprising a signal governing traffic over the switch, mechanism for opening the switch operative only when said signal indicates "stop", a device controlling the operation of the mechanism, and train carried means controlling the operation of said device. 10

3. A railroad switch operating system comprising a signal governing traffic over the switch, mechanism for opening the switch operative only when said signal indicates "stop", a relay controlling the operation of said mechanism, and inductive means controlling the operation of said relay. 15

4. A railroad switch operating system comprising a signal governing traffic over the switch, mechanism for operating said switch, a device controlling the operation of said mechanism, and train operated inductive means controlling the operation of said device, said mechanism being operative to open said switch only when said signal is at "stop" and said device is energized. 25

5. In combination, a stretch of railway track, a traffic governing device associated with said stretch, a railway vehicle, a manually controllable device carried on said vehicle, a stick relay, a pick-up circuit for said relay controlled by said manually controllable device, a stick circuit for said relay controlled by track circuit conditions in said stretch, and means controlled by said relay for controlling said traffic governing device. 30

6. In combination, a stretch of railway track comprising a first section and a second section, a track switch in said first section, a railway vehicle, a manually controllable device carried on said vehicle, a stick relay, a pick-up circuit for said relay controlled by said manually controllable device and by traffic conditions in said second section, a stick circuit for said relay controlled by traffic conditions in said first section, and means controlled by said relay for controlling said switch. 35

7. In combination, a stretch of railway track comprising a first section and a second section as well as a third section, a track switch in said first section, a railway vehicle, a manually controllable device carried on said vehicle, a trackway device 50 located in said third section and controlled by said manually controllable device, a stick relay, a pick-up circuit for said relay controlled by said trackway device and by track circuit conditions in said second section, a stick circuit for said relay controlled by track circuit conditions in said first section, and means controlled by said relay for controlling said switch. 55

8. In combination, an electrical device, a stick relay, a manually controllable device, a second 60 manually controllable device, a pick-up circuit for said relay controlled by said first manually controllable device, a stick circuit for said relay controlled by said second manually controllable device, means controlled by a front contact of said relay for controlling said electrical device in a given manner, and means controlled by a back contact of said relay for controlling said electrical device in a second given manner. 65

9. In combination, a stretch of railway track, 70 a governing device for controlling traffic movements in said stretch, a railway vehicle, a manually controllable device carried on said vehicle, a second manually controllable device located at a point along said stretch, means controlled by said 75

first manually controllable device for operating said governing device in a given manner, and means controlled by said second manually controllable device for operating said governing device in a second manner.

10. In combination, a railway track switch, a signal for governing traffic movements over said switch, a control circuit for said signal, a locking relay controlled by traffic conditions and by said signal control circuit, a second locking relay controlled by said first locking relay and by traffic conditions, and means controlled by said second locking relay for controlling said switch.

11. In combination, a stretch of railway track 15 containing a switch, a vehicle movable over said stretch, a trackway device located along said stretch, a magnet carried on said vehicle and movable into a first or a second position on said vehicle so as to be in inductive relation or out 20 of inductive relation respectively to said trackway device when said vehicle moves over said stretch, and means controlled by said trackway device for operating said switch from a first to a second position if and only if said magnet is 25 in inductive relation to said trackway device when said vehicle moves over said stretch.

12. In combination with a section of railway track including a track relay and provided with a traffic governing device, governing means controlled manually from a remote point, a stick relay having a pickup circuit and a stick circuit one controlled by said governing means and the other controlled by said track relay, and an operating circuit for said device distinct from said pickup and stick circuits and controlled by said stick relay.

13. In combination, a section of railway track provided with a traffic governing device and with a track circuit including a track relay, a manually operable device, a second manually operable device, a stick relay having a pickup circuit controlled by said first manually operable device but not by said track relay and having a stick circuit controlled by said second manually operable 45 device and by said track relay, and means controlled by said stick relay for controlling said traffic governing device.

14. In combination, a section of railway track provided with a traffic governing device and provided with a track circuit including a track relay, a second section of track adjacent said first

section provided with a second track circuit including a second track relay, a manually operable device, a stick relay, a pickup and a stick circuit for said stick relay one of which is controlled by said manually operable device and by said second track relay and the other of which is controlled by said first track relay, and means controlled by said stick relay for controlling said traffic governing device.

15. In combination, a section of railway track 10 provided with a traffic governing device and provided with a track circuit including a track relay, a second section of track adjacent said first section provided with a second track circuit including a second track relay, a manually operable 15 device, a stick relay, a pickup and a stick circuit for said stick relay one of which is controlled by said manually operable device and by said first track relay and the other of which is controlled by said second track relay, and means controlled by said stick relay for controlling said traffic governing device.

16. In combination, a section of railway track provided with a traffic governing device and provided with a track circuit including a track relay, 25 a second section of track adjacent said first section provided with a second track circuit including a second track relay, a manually operable device, a second manually operable device, a control relay, a first and a second circuit for energizing said control relay one of which is controlled by said first track relay and by said first manually operable device and the other of which is controlled by said second track relay and by said second manually operable device, and means controlled by said control relay for operating said traffic governing device.

17. In combination, a section of railway track provided with a railway traffic governing device and with a track circuit including a track relay, 40 a manually operable device, a second manually operable device, a stick relay having a pick-up and a stick circuit one of which is controlled by said first manually operable device and by said track relay and the other of which is controlled by said second manually operable device, and an operating circuit for said traffic governing device distinct from said pick-up and stick circuits and controlled by said stick relay for controlling said traffic governing device.

50 HARRY E. BRASHARES.
